UNITED STATES PATENT OFFICE.

ARMIN ELMENDORF, OF CHICAGO, ILLINOIS.

VENEER BOX AND PANEL FOR MAKING THE SAME.

Application filed November 30, 1925. Serial No. 72,087.

It is at present common practice to make boxes, adapted to serve as shipping containers, out of thin sheets of wood, such as wood veneer; the four side walls being bound together by hoops of wire. Each side wall of such a box must be made either of a single sheet or of several sheets whose combined widths will be equal to the width of the wall; thus using up the workman's time in selecting the thin boards or sheets and fitting or trying them until the proper combination is obtained.

The object of the present invention is to make the side walls of a veneer box from a single continuous sheet instead of a plurality of separate side panels.

A further object of the present invention is to build a veneer box with sides composed of a single continuous panel made from pieces selected haphazardly and without regard to width; thereby permitting the utilization of materials that have heretofore been wasted, and at the same time reducing the labor cost in assembling for widths.

The ordinary wire-bound boxes as heretofore made, with single-ply walls, have open joints at the corners and between the meeting edges of the sheets or strips of veneer; and, wherever there may happen to be a knot hole, there is of course an opening through the wall of the box. A still further object of the present invention is to produce a cheap and simple wire-bound box out of waste or low grade material that may be split or contain knot holes; without leaving any openings of an objectionable size through the walls of the box.

In carrying out my invention, I form the veneer into a panel, with the grain extending diagonally of one of the major axes of the panel. The panel is then bent along lines parallel with such axes. If the grain extended in the direction of the lines along which the panel is to be bent, the wood would split at the bends. On the other hand, if the grain extended at right angles to the lines on which the bends are made, the fibres would break so as to leave corners that would be rough, very weak, and containing openings or cracks. However, as the line on which a bend is made recedes from either of the two extreme conditions just mentioned, the aforesaid objections become less pronounced. I have found that the best results are obtained when the bend is made along a line at an angle of in the neighborhood of

twenty degrees to the grain. When veneer is bent along such a line, there is a minimum breaking of the fibres and a smooth, strong and tight corner is produced. When the veneer lies in a plurality of layers, the grain in one or more of the layers should cross that in another layer at an angle of about forty degrees, so that the bends may be made along lines bisecting this angle, causing each corner to lie at an angle approximately twenty degrees to the grain in each layer.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is an elevation of a fragment of a panel composed of a single layer of veneer composed of strips laid edge to edge; Fig. 2 is a view similar to Fig. 1 showing a two-ply panel, a part of the front ply or layer being broken away; Figs. 3 and 4 are views similar to Fig. 1, each showing a fragment of a panel and a different way of fastening the strips together; Fig. 5 is a view similar to Figs. 1 to 4, showing a covering element for the fastening means, whereby a smooth continuous face may be obtained on one side of the panel; Fig. 6 is a section, on an enlarged scale, showing a fragment of the panel illustrated in Fig. 5; Fig. 7 is a section on an enlarged scale, along a line at right angles to the line on which a bend is to be made, showing the manner in which the panel is prepared before making the bend; Fig. 8 shows the panel of Fig. 7, after the bend has been made; Fig. 9 is a top plan view of one corner of a box made from one of my improved panels; Figs. 10, 11 and 12 are vertical sections through the top of a box, at one side thereof, showing three different ways of reinforcing the box; Fig. 13 is a perspective view of a metal tie having self-contained fastening means, to be employed either for fastening the strips of a panel together or for reinforcing a box at the ends; and Fig. 14 is a perspective view of a box made from one of my improved panels.

Referring to Fig. 1 of the drawings, 1, 1 represent a series of strips or narrow sheets of veneer or other fibrous material laid edge to edge. The grain is assumed to extend in the general direction of the length of each

strip or sheet so that, when the material is laid with its long edges at an angle of about seventy degrees to one of the long edges A of the panel to be formed therefrom, the grain 5 will lie at that angle to one of the major axes of the panel and at an angle of twenty degrees to the other major axes. The strips may be fastened together in a suitable way. In the arrangement shown, they are sewed 10 together, as indicated by the broken lines 2, 2 that extend parallel with the long edges of the panel.

In Fig. 2 the panel is made of two layers, each consisting of a group of strips or narrow sheets, those in one group being indicated at 3, 3 and the other at 4, 4. The grain in each group or series lies at the proper angle to the long edges B, B of the panel, but the strips or narrow sheets are laid across each 20 other. The strips of each series may be fastened to each other and to those of the other series in any suitable way as, for example, by means of rows of stitching 2, 2. The stitching need not be in rows, but may extend 25 in any desired fashion over the entire or any part of the surface of the panel. Such an arrangement is shown in Fig. 3, in which the broken lines 5 represent the stitching.

In Fig. 4 I have illustrated what I believe 30 to be the most practical fastening means. Instead of stitching the veneer, I lay fine wires 6 upon the strips or sheets, the wires extending parallel with the long edges of the panel. These wires are then secured in place 35 by means of numerous small staples 7 spaced only a short distance apart from each other. I am enabled to use a much lighter wire than that required for the ordinary wire-bound boxes, because my improved method of positioning the veneer with respect to its grain, gives to the walls and corners of the box an inherent strength not possessed by similar walls in which the grain lies parallel to the corners.

45 In some instances it is desirable to have a panel or the walls of a box present a smooth face or faces to receive printing or the like. In such cases, a sheet of paper or other flexible material, such as indicated at 8 in Fig. 5 may be cemented to that face of the panel across which the wires extend. The wires and the staples are small and therefore when 50 the paper is applied and subjected to a considerable pressure, the wires will be pressed down into the veneer, as best shown in Fig. 6, leaving the surface of the finished panel substantially smooth.

60 It will be seen that when a panel is made of a plurality of plies, with the strips in one ply crossing those in the other, not only will the joints between the strips in one ply be substantially closed by the strips in the other 65 ply, but knot holes and cracks will be similarly covered; thus permitting the use of stock that would ordinarily be unsuitable

for box making. Again, since the width of any particular strip or group of strips is not required to bear any definite relation to the width of the side of a box or the like, the strips or narrow sheets, in assembling them 70 in a panel, may be picked up at random and without regard to their widths.

Before bending one of my improved panels, I prefer to crease it, by pressing a bar or other member having a rounded edge heavily 75 against the same at each line along which a bend is to be made, while the panel is being solidly supported from the other side. In Fig. 7 I have shown a fragment of a two-ply panel prepared for bending. It will be 80 seen that one face of the panel is flat while the other has a rounded groove or depression 9 formed therein. When the panel is bent along the line of the groove, with the groove on the inner side of the angle, a condition is brought about as shown in Fig. 8; the corner being slightly rounded on the outside and the opposite sides of the groove being brought close together so as to substantially close the groove. If desired, the bend 90 may successfully be made with the groove on the outer side.

When a box, say a rectangular box, is to be formed, a panel is cut of the proper width and of a length somewhat greater than the 95 circumference of the box. The lines of depression are then formed at the proper points, and the panel is bent into the form of a shell, preferably with the meeting ends overlapping at one corner, as shown in Fig. 14. In the top and bottom of the shell there will be placed suitable heads or ends of any 100 desired kind. In the arrangement shown each head consists of a reinforcing frame 10, that may be the cleats that are ordinarily 105 used for this purpose, and a board or panel 11 located on the inner side of the frame. The sides of the box may be nailed to the heads such nails being shown at 12 in Fig. 9. The raw edge that would otherwise be left 110 on that end of the panel that overlaps the other end may be avoided by pasting or gluing a tape of paper or cloth 13 across the exposed edge of the panel, as shown in Fig. 9.

If desired, the top and bottom edges of the 115 sides of the box may be covered by a tape of paper, cloth or other flexible material laid upon each of these edges and folded down along each side of the panel, such a tape being 120 shown at 14 in Fig. 11. Staples 15 or nails 125 may be driven through the taped portions into the cleats or frames. In Fig. 10 there is shown another way of finishing and reinforcing the top and bottom; there being a metal band 16 extending around the box at the top and the bottom and there being nails 17 or other fastening means passing through this band, through the sides of the box, and into the cleats or frames. Instead of the band 130 nailed in place as shown in Fig. 10, I may em-

ploy a band such as shown in Fig. 13, 18 indicating the band and 19 being prongs struck out of the metal of the band and projecting laterally therefrom. Such a band as this 5 could also be used, in a light form, for fastening the pieces of veneer together, instead of the stitching or wires.

Instead of using a flat metal band around the ends of the box, I may employ a wire, such 10 as indicated at 20 in Fig. 12; this wire being held in place by staples 21 that extend through the veneer and into the cleats or frames.

I claim:

15 1. A device comprising two walls at an

angle to each other made of a plurality of layers of veneer lying upon each other with the grain crossed at an angle of approximately forty degrees and bent along a line that approximately bisects such angle. 20

2. A box blank in the form of a panel made of strips of veneer arranged edge to edge and secured together, the panel having the fibres compressed to form a rounded groove extending across one side at an angle 25 of about twenty degrees to the fibres.

In testimony whereof, I sign this specification.

ARMIN ELMENDORF.
